LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

CUSHIONING DEVICE FOR ROCK DRILLS.

Application filed November 12, 1921. Serial No. 514,649.

To all whom it may concern:

Be it known that I, LEWIS C. BAYLES, a citizen of the United States, a resident of Easton, county of Northampton and State 5 of Pennsylvania, have invented a certain Cushioning Device for Rock Drills, of which the following is a specification, accompanied by drawings.

This invention relates to fluid actuated 10 rock drills of the hammer type, but more particularly to a machine having motive fluid control like that disclosed in U. S. Patent No. 1,268,081, granted to me, June 4, 1918, in which there is a fluid actuated exhaust valve. A suitable reciprocating exhaust valve for such a machine is disclosed 15 in U. S. Patent No. 1,278,237, granted September 10, 1918, to Fred M. Slater, both of said patents having been assigned to Ingersoll-Rand Co.

With rock drills of this type, as with other types, the character of the ground is sometimes such that trouble is experienced in extracting the drill steel from the hole, 25 and it is then customary to continue to run the machine while backing out of the hole, so that the vibration and rotation help to extract the drill steel. But in such cases, the piston striking the front end parts of the 30 machine, produces excessive shock and vibration causing breakage.

The primary object of the present invention is to create a cushion for the piston in the forward end of the cylinder, in order to 35 prevent the piston from striking the front head parts and thus preventing the excessive shock and strain throughout the entire machine, when the drill steel is moved forward out of the path of the piston, as in the 40 case when backing out of a tight drill hole.

By closing communication between the auxiliary exhaust port from the front end of the cylinder and the atmosphere, a cushion is formed in front of the piston head, and 45 one suitable and convenient way of closing such communication is to provide a manually operated valve locking device by means of which the exhaust valve may be held from reciprocation in one direction, closing 50 the auxiliary exhaust to atmosphere from the front end of the cylinder while maintaining the auxiliary exhaust open to atmosphere from the rear end of the cylinder. The piston hammer continues to reciprocate 55 rapidly as a differential valveless hammer,

but the pressure of the expanding air on the larger forwardly acting pressure surface of the piston head is rapidly dissipated through the open auxiliary exhaust from the rear end of the cylinder, and as there is 60 a strong cushion created in front of the piston head, due to the closing of the auxiliary exhaust to atmosphere at that end of the cylinder, the blow on the drill steel is light 65 if the shank of the drill steel extends all the way into the cylinder, and the piston does not strike the front head parts. If the drill steel is pulled outwardly, out of the path of the piston, the cushion still has the important function of preventing the piston 70 from striking any of the front head parts.

A machine embodying my invention in one operative form is shown in the accompanying drawings, it being understood that various equivalent devices may be designed 75 for accomplishing my purposes, without departure from the spirit of my invention as disclosed in this specification and defined in the appended claims.

In the drawings, Figure 1 is a side view 80 partly in longitudinal section of a rock drill on the line 1—1 of Figure 2, looking in the direction of the arrows,

Figure 2 is a detail horizontal sectional plan view taken through the exhaust valve 85 of Figure 1, with the valve locking device in locking position, and

Figure 3 is a detail sectional view of a portion of Figure 2 showing the valve locking device in withdrawn or unlocked position, so that the valve may function normally. 90

Referring to the drawings, the cylinder A of the rock drill is provided with a differential piston hammer B having the main head C, the smaller rear head D connected to the main head by the reduced neck E and the forward piston extension F having the flutes G. 95

Automatic rotation is provided by the usual rifle bar H extending rearwardly through the rotation washer J into the rotation ratchet K, the details of which are not shown as they form no part of the present invention. The back end of the machine 100 is closed by the back head L, having the water connection O and the water tube cap P. 105

The forward piston extension F extends 110 through the front cylinder bushing or

washer Q into the chuck nut R threaded to the chuck S in the front head T. The lugged shank U of the drill steel V extends through the chuck key W, the chuck front bushing X and the chuck back bushing Y into position to receive the blows of impact of the hammer piston. The forward end of the water tube Z is shown extending into the hollow drill steel. Motive fluid is supplied to the machine at the inlet *a* controlled by the throttle valve *b* and constant pressure is maintained on the forwardly acting pressure surface *c* of the smaller piston head D. Motive fluid is alternately supplied to and exhausted from the opposite pressure surfaces *d* and *e* of the main piston head C, by suitable ports and passages controlled by the piston. Motive fluid is supplied to the front end of the cylinder through the longitudinal passage *f*.

A main free exhaust port *g* is located centrally of the cylinder communicating with the atmosphere at the port *g'* for exhausting on each side of the piston head C, and a valve controlled auxiliary exhaust is also provided from each end of the cylinder, as indicated by the rear auxiliary exhaust *h* and the forward auxiliary exhaust *j* in the form of ports and passages.

The automatic fluid actuated exhaust valve *k* is preferably located in a valve chest *o* formed transversely in the cylinder A. A valve *k* may be formed in two parts slidably mounted on the bolt *p* on which they reciprocate in normal operation. The bolt is provided with a head *q* a valve stop *r*, a rubber washer *s*, a valve chest cover *t*, a lock washer *u*, and a nut *v* for holding the parts together.

So far described, the machine does not differ materially from the type of rock drill described in U. S. Patents, 1,268,081, and 1,278,237 hereinbefore referred to. In order, however, to create a cushion in front of the main piston head C under certain conditions which have been described, I provide means suitably and conveniently mounted on the valve bolt head *q* for forcing and holding the valve *k* in one position as indicated for instance in Figure 2, so that the valve cannot reciprocate and at the same time closes communication between the forward auxiliary exhaust passage *j*, and atmosphere, while maintaining the rearward auxiliary exhaust passage *h* open to atmosphere. Under such circumstances, the hammer piston will continue to reciprocate rapidly, performing its functions as a differential valveless piston, but a cushion is formed in front of the main piston head C owing to the closure of the forward auxiliary exhaust *j* to atmosphere and the piston head does not strike the front end parts of the machine. Such a condition is shown with the parts in positions indicated in Fig-

ure 1, it being assumed that the exhaust valve is locked in the position indicated in Figure 2. With the shank of the drill steel all the way in the front head, as indicated in Figure 1, a light blow will be struck on the drill steel by the hammer piston, due to the fact that the pressure behind the main piston head C will be rapidly dissipated through the open auxiliary exhaust passage *h* leading from the rearward end of the cylinder, and also due to the fact that the cushion is formed at the front of the piston head. When the drill steel is withdrawn forwardly in the chuck, out of the path of the piston, the cushion in front of the main piston head continues to prevent injury to the front head parts.

Any suitable and conveniently manipulated device may be provided for locking the valve in a given position and in this instance, I have chosen to show the locking pin *w* movable longitudinally in a hole formed partly in the head and shank of the valve bolt *p* and partly in an extension *y* extending from said bolt head *q*, so that the head *z* of the locking pin may be moved against the valve *k* to force the valve into the position indicated in Figure 2. A transverse pin 2 limits the outward movement of the locking pin and a spring pressed stop 3 is adapted to engage behind the beveled head *z* of the locking pin to hold the pin in locked position, but permit the pin to be readily withdrawn past the stop 3 to unlocked position as indicated in Figure 3. For manipulating the locking pin, a hollow nut or cap 4 preferably riveted to the end of the locking pin, as by means of the rivet 5, is adjustable on the bolt head extension *y* as by means of the screw threads 6. Manual rotation of the hollow nut 4 moves the locking pin inwardly and outwardly as desired.

I claim:

1. In a fluid actuated rock drill of the hammer type, the combination of a cylinder having a central exhaust port, a piston controlling said exhaust port and adapted to compress motive fluid at either end of said cylinder upon closing said exhaust port, an auxiliary fluid actuated exhaust valve to relieve such compression, a stop to prevent the operation of said valve for cushioning the front end of the cylinder and having a reduced portion, and means cooperating with said reduced portion for limiting movement of the stop.

2. In a fluid actuated rock drill of the hammer type, the combination of a cylinder having a central exhaust port, a piston controlling said exhaust port and adapted to compress motive fluid at either end of said cylinder upon closing said exhaust port, an auxiliary fluid actuated exhaust valve to relieve such compression, a stop to prevent the operation of said valve for cushioning

only the front end of said cylinder and having a reduced portion, a pin cooperating with said reduced portion for preventing removal of the stop, and automatic means for locking the stop in position.

3. In a fluid actuated rock drill of the hammer type, the combination of a cylinder having a central exhaust port, a piston controlling said exhaust port and adapted to compress motive fluid at either end of said cylinder upon closing said exhaust port, an auxiliary fluid actuated exhaust valve to relieve such compression, a stop to prevent the operation of said valve for cushioning only the front end of said cylinder and having a reduced portion, a pin cooperating with said reduced portion for preventing removal of the stop, a spring pressed plunger for locking the stop in position, and a cap on the stop for manipulating said stop.

4. In a fluid actuated rock drill of the hammer type, the combination of a cylinder

having a central exhaust port, a piston controlling said exhaust port and adapted to compress motive fluid at either end of said cylinder upon closing said exhaust port, an auxiliary fluid actuated exhaust valve to relieve such compression, a bolt on which said valve is adapted to slide, an extension on said bolt, a stop in said extension to lock said valve for cushioning the front end of the cylinder, said stop having a reduced portion, a pin extending transversely through said bolt and cooperating with the reduced portion for preventing removal of the stop, a spring pressed plunger to cooperate with the reduced portion for locking the stop in position, and a cap secured to the stop and cooperating with the extension for manipulating the stop.

In testimony whereof I have signed this specification.

LEWIS C. BAYLES.
